CONDIMENT DISPENSER

John F. Bonistall, Zanesville, Ohio, assignor to Shawnee
Pottery Company, Zanesville, Ohio, a corporation of Ohio

Application March 1, 1955, Serial No. 34,816

Term of patent 14 years

(Cl. D44—22)

Fig. 1

Fig. 2

Fig. 4

Fig. 1 is a perspective view of a condiment dispenser showing my new design, the essential features of which are disclosed in full lines in the drawing;

Fig. 2 is a perspective view thereof from the opposite side;

Fig. 3 is a bottom plan view; and,
Fig. 4 is an end elevation.

I claim:

The ornamental design for a condiment dispenser, as shown and described.
